UNITED STATES PATENT OFFICE.

EDWARD WALTERS, OF CHICAGO, ILLINOIS.

YOKE FOR DRAW-BARS.

1,135,474.

Specification of Letters Patent. Patented Apr. 13, 1915.

Application filed March 14, 1912. Serial No. 632,677.

To all whom it may concern:

Be it known that I, EDWARD WALTERS, a citizen of the United States, and resident of Chicago, in the county of Cook and State of Illinois, have invented certain new and useful Improvements in Yokes for Draw-Bars, of which the following is a specification.

My invention relates to draft rigging and has particular reference to a novel yoke for use in connection therewith.

As is well known, the connection between the draw-bar shank and the yoke has long been a source of difficulty due to the extreme strains in service applied both in pulling and buffing. These strains are still more difficult to handle when the force is applied at an angle to the longitudinal center line of the draw-bar and rigging. This latter strain results frequently in destroying the connection between the draw-bar and yoke.

It is one of the principal objects of my invention to provide a yoke which shall enable a practically indestructible connection to the draw-bar, a connection as strong and rigid as if the parts were cast together. This object is attained by forming the yoke in two parts, the division being on the longitudinal vertical center line of the yoke. Thus it will be seen two equal halves are formed and these halves being duplicates, but one pattern need be prepared. On the forward end of each of the halves is provided hooks for engagement with the abutments on the draw-bar and means are provided for uniting the two halves. The forward ends bearing the hook portions are united by webs carrying a key, the webs assuring still further rigidity.

My invention will be more readily understood by reference to the accompanying drawings, wherein,

Figure 1 is a side elevation of a yoke constructed in accordance with my invention; Fig. 2 is a plan view of the construction shown in Fig. 1; Fig. 3 is a section on the line 7—7 of Fig. 1, and Fig. 4 is a section on the line 8—8 of Fig. 1.

Referring more particularly to the drawings Figs. 1 to 4 inclusive it will be seen that a draw-bar 10 is provided with the usual abutments 11 and with a key slot 12. My

novel yoke is composed of equal halves 13, having perforated ears 14, 15, at the front and rear. Through the openings in the ears I place bolts 16, by means of which the halves may be securely united. The forward ends of each of the halves are provided with inturned hooks 22, co-operating with the abutments 11 on the draw-bar. Uniting the forward ends in a vertical line is a web 23 having integral therewith and projecting inwardly therefrom a lug forming a portion of a key, 24, which key, when the parts are in operative condition enters the slot 12 in the draw bar and receives its share of the strains.

It will be seen that to assemble the yoke on a draw-bar the two halves are placed on opposite sides of the draw-bar with the integral keys in register with the slot in the draw-bar, driven in place and the bolts 16 attached.

It will be seen that by the construction described I am enabled to secure an extremely rigid and strong connection between the draw-bar and yoke and one relying for its stability on no bolts or rivets which are under strain. The bolts 16 are not under strain at any time and therefore are not subject to wear.

While I have described the yoke as being divided vertically on its longitudinal center line it will be understood that this might be varied by shifting the line of division to one side or the other and that other modifications may be made, all without departing from the spirit of my invention.

I claim:

A yoke having a spring-receiving loop and means for attachment to a draw-bar, said yoke being formed in two parts by means of a longitudinal, vertical division, said draw-bar attaching means including a divided key, one part of the key being rigid with each of the two parts of the yoke, substantially as described.

EDWARD WALTERS.
